UNITED STATES PATENT OFFICE.

GORDON K. WRIGHT, OF HINSDALE, ILLINOIS, ASSIGNOR TO CHICAGO MANUFACTURING & DISTRIBUTING COMPANY, A CORPORATION OF ILLINOIS.

RATCHET-WRENCH.

1,089,737.

Specification of Letters Patent. Patented Mar. 10, 1914.

Application filed March 19, 1913. Serial No. 755,350.

To all whom it may concern:

Be it known that I, GORDON K. WRIGHT, a citizen of the United States, and resident of Hinsdale, county of DuPage, and State of Illinois, have invented certain new and useful Improvements in Ratchet-Wrenches, of which the following is a specification, and which are illustrated in the accompanying drawings, forming a part thereof.

10 The invention relates to wrenches and more particularly to those having a socket for application to the member which is to be rotated and ratchet mechanism permitting a reverse movement of the handle without removing the socket from such member.

15 The object of the invention is to provide a wrench which shall be of simple and inexpensive construction and efficient in operation.

20 The invention is exemplified in the structure to be hereinafter described, and which is illustrated in the accompanying drawings, wherein—

25 Figure 1 is a side elevation showing a wrench embodying the features of improvement provided by the invention and details of a nut and bolt to which the wrench may be applied. Fig. 2 is a plan view of the wrench showing one of the parts removed 30 and certain other parts in section. Figs. 3 and 4 are sectional views taken on the lines 3—3 and 4—4, respectively of Fig. 2, and Fig. 5 is a perspective view showing a detail of the construction.

35 The wrench is shown in the drawings as comprising a handle, 10, and a head which is generally designated 11. For convenience in construction the head, 11, will preferably comprise a pair of side plates shown 40 at 12 and 13. These side plates are spaced apart a sufficient distance to receive a pawl, 14, between them, and one of the plates, as 12 is shown as being formed integral with the handle, 10. The other side plate, 13, is 45 preferably separately formed from the handle, but is firmly held in position when the parts are assembled, as by rivets 15 and 16.

50 The rivets, 15, 16, are passed through the side plates 12 and 13, and through the spacing members, as 17 and 18 between the plates. The spacing members, 17 and 18, serve to maintain the plates at the required separation to permit of the operation of the 55 pawl, 14, between them. As shown, these

spacing members are both formed integral with the plate 12 and handle 10, and one of them, as 17, is made round to serve as a pivot for the pawl. The other spacing member, 18, has a configuration similar to 60 that of the pawl, 14, and constitutes a closure for the space between the plates at that side remote from the pawl.

The pawl, 14, coöperates with the teeth of a ratchet, 19. This ratchet is formed upon 65 the periphery of a sleeve, 20, which is rotatably mounted in the head, 11. Preferably the two side plates 12 and 13 of the head, 11, are apertured, as indicated at 21 and 22, to provide bearings for the opposite ends of the sleeve, 20. The ratchet, 19, being formed upon the sleeve 20, between the plates 12, 13, serves to prevent displacement of the sleeve when the plates are held together by the rivets 15 and 16. A spring, 75 23, located between the side plates 12 and 13 and reacting between the rear end of the pawl, 14, and the inner face of the spacing member, 18, serves to hold the pawl in operative engagement with the ratchet, 19. 80

A socket, 24, will usually be employed for engagement with the member to be turned, as the nut X. In order that this socket may be located at either side of the head, 11, it is preferably provided with a stem, 35, 85 adapted to removably enter the bore of the sleeve, 20. To prevent relative rotation of the socket, 24, and sleeve, 20, the stem 25 of the socket and the bore of the sleeve are of corresponding angular shape. A leaf 90 spring, 26, located in a recess, 27, in the wall of the sleeve, 20, and protruding into the bore of the sleeve engages the stem, 25, of the socket member to yieldingly hold the latter against removal. As shown, the spring, 95 26, is held in position by a rivet, 28, passed through one end of the spring and into the wall of the sleeve. Most desirably the stem, 25, of the socket member, 24, is made tubular to receive the protruding end of a 100 bolt, as Y, upon which the nut, as X runs.

In the use of the wrench, the socket member, 24, will be applied to that side of the head, 11, adapted to permit the pawl, 14, to turn the ratchet, 19, in such direction as it is 105 desired to turn the nut, as X to which the wrench is to be applied. For this purpose, the stem, 25, of the socket member, 24, is passed into the bore of the sleeve, 20, from the side at which the socket member, is de- 110

sired to be located. The arrangement by which the socket member, 24, may be located at either side of the head, 11, permits the use of the wrench, with but a single 5 pawl, 14, for turning the nut, as X in either direction.

The device is accordingly of simple construction and all of its parts may be made from cast metal without finishing with machine tools. The construction of the spacing member, 17, whereby it serves as a pivot for the pawl, 14, provides increased strength, as also a free movement of the pawl. Furthermore, the inner end of the handle, 10, provides a shoulder, 29, part of which is in a direct line with the thrust of the pawl. The wrench may be conveniently used for the turning of nuts which are located in difficultly accessible positions. The use of 20 the socket, 24, for engaging the nut to be turned and the provision of the tubular shank, 25, permit the nut X and protruding portion of the bolt Y to effectively hold the wrench in position when it is once applied. The entire attention of the operator may accordingly be given to the turning of 25 the handle, 10. If desired, a plurality of sockets of different size but having stems, as 30 25, of like dimension may be interchangeably used for engagement with nuts which differ in size or shape.

I claim as my invention—

1. In a ratchet wrench, in combination, a handle, a pair of parallel plates at one end 35 of the handle, one being formed integral with the handle and the other being removable, a socket member extending transversely through the plates and being journaled therein, ratchet teeth formed on such 40 member between the plates, a tubular spacing stud formed integral with that one of said plates which is formed integral with the handle and extending toward the other plate, a pawl pivotally mounted on the said stud, and a bolt or rivet connecting the 45 plates and extending through the bore of the said stud.

2. In a ratchet wrench, in combination, a handle, a pair of apertured parallel plates 50 at one end of the handle, one being formed integral with the handle and the other being removable, a sleeve journaled in the apertures of the plates, ratchet teeth formed on the sleeve between the plates, a nut engaging socket having an axially extending

tubular stem adapted to enter the said sleeve from either end, the bore of the said stem being adapted to receive the rod or bolt upon which a nut runs for guidedly supporting the socket when engaged with the nut, a 60 tubular spacing stud formed integral with one of the said plates, a pawl acting in one direction only pivotally mounted on the said stud and cooperating with the said ratchet teeth and a bolt or rivet connecting the 65 plates and extending through the bore of the said stud.

3. In a ratchet wrench, in combination, a handle, a pair of parallel plates at one end of the handle, one being formed integral 70 with the handle and the other being removable, a socket member extending transversely through the plates and being journaled therein, ratchet teeth formed on such member between the plates, an integral spacing 75 flange extending along one edge of that one of the said parallel plates which is formed integral with the handle from the handle to a point adjacent the socket member, said flange having an inwardly extending thickened portion which is spaced apart from the end of the handle, an integral spacing stud formed on the same plate with the said flange at an equal distance from the end of the handle with the said thickened portion 80 of the flange, a pawl having an apertured hub intermediate its ends, the said hub being mounted on the said spacing stud and the two end portions of the pawl extending along the adjacent edge of the plate which 85 carries the stud toward the adjacent end of the handle and toward the said socket member respectively, a spring transversely mounted in the space between the said plates, the end of the handle, the thickened 90 portion of the said spacing flange and the hub of the pawl, the opposite ends of the spring reacting against the said spacing flange and the adjacent end of the pawl respectively, and two fastening elements uniting the said plates, one extending through the said removable plate into the thickened 95 portion of the said spacing flange and the other extending through the removable plate into the said spacing stud. 100
